CROSS CRIMP-SEALED PACKAGE

Leroy L. Salfisberg, South Orange, N. J.; Herman G. Kopald and Lloyd I. Volckening, executors of said Leroy L. Salfisberg, deceased, assignors to Ivers-Lee Company, Newark, N. J., a corporation of Delaware

Application April 10, 1948, Serial No. 145,630

Term of patent 14 years

(Cl. D58—2)

To all whom it may concern:

Be it known that I, Leroy L. Salfisberg, a citizen of the United States of America, and a resident of South Orange, in the county of Essex and State of New Jersey, have invented a new, original, and ornamental Design for a Cross Crimp-Sealed Package, of which the following is a specification, reference being had to the accompanying drawings, forming part thereof.

Fig. 1 is a plan view of a cross crimp-sealed package, showing my new design;

Fig. 2 is an edge elevational view thereof, the other edge of the package being the same;

Fig. 3 is a greatly enlarged plan view of the portion of the package bounded by the lines 3—3 of Fig. 1;

Fig. 4 is a similar view of the portion of the package bounded by the lines 4—4 of Fig. 1; and

Fig. 5 is an enlarged fragmentary transverse sectional view approximately on the plane of the line 4—4 of Fig. 1.

I claim:

The ornamental design for a cross crimp-sealed package, as shown.

LEROY L. SALFISBERG.
